UNITED STATES PATENT OFFICE.

JOHN OLIVER WESNER, OF CAMERON, SOUTH CAROLINA.

BED-BOTTOM.

No. 868,951.

Specification of Letters Patent.

Patented Oct. 22, 1907.

Application filed June 21, 1907. Serial No. 380,073.

To all whom it may concern:

Be it known that I, JOHN O. WESNER, a citizen of the United States, residing at Cameron, in the county of Orangeburg and State of South Carolina, have invented 5 certain new and useful Improvements in Bed-Bottoms; and I do hereby declare the following to be a full, clear, and exact description of the invention, such as will enable others skilled in the art to which it appertains to make and use the same.

10 This invention relates to bed bottoms provided with springs; and it consists of a novel locking-wire for preventing the springs from being displaced.

In the drawings, Figure 1 is a plan view of a portion of a bed bottom constructed according to this invention.

15 Fig. 2 is a detail side view of one of the locking wires. Fig. 3 is an end view of the locking wire.

A is a portion of a wire frame of any approved construction which extends around the springs.

20 B and B' are portions of two adjacent springs, which are of any approved helical form. The top coil or convolution only is shown, for clearness.

C is a key wire which extends crosswise of the springs and which has its ends secured to the wire frame A in any approved manner.

25 D is the novel locking wire. This locking wire extends crosswise of the key wire and its ends are secured to the wire frame in a similar manner. The locking wire is used in connection with the key wire to lock the top coils of two adjacent springs, and also to lock the

30 coil of each outer spring to the wire frame which comes adjacent to it. The locking wire D has a loop provided with side portions d which are arranged at an angle to the main portion of the locking wire. This loop has concavo-convex humps e in its main portion where the

35 said main portion joins onto the loop, and these humps engage with the top coil of one of the springs B. The middle portion of the said loop is bent around to form a hook f which engages with the wire of the frame or with the wire of the next adjacent spring. The extreme

40 point of the hook is bent over the wire with which the said hook engages sufficiently far to form a channel g

for engaging with the key wire C. The key wire is preferably arranged under the top coils of the springs, and the locking wire is preferably arranged with its main portion nearly at a tangent to the top coils of one 45 row of springs and so that its concavo-convex humps hook over the top coils of the said springs. The side portions d of the loops of the locking wire are arranged below the top coils of the springs, and the hooks of the said loops are bent over the top sides of the said coils 50 or over the top of the wire which forms the frame. The side portions d of the loops are angle-shaped so that they have knees d' below the level of the point of the hook f and so that a space h is formed between the point of the hook and the side portions d, as shown in Fig. 3. 55

The locking-wires D are formed by machinery with the humps, hooks and loops complete, and the knees d' enable the top coils of the springs, and the frame A, to be slipped into engagement with the said hooks f, so that the locking-wire does not have to be bent by hand 60 when the parts are assembled in a bed-bottom. When the locking wires are constructed in this manner and applied to the springs and frame as set forth, the springs are retained in position in a more advantageous manner than heretofore, as they cannot be displaced 65 in any direction.

What I claim is:

The combination, with the coil of a spring, and a wire arranged adjacent thereto; of a key wire which extends crosswise of the said parts, and a locking wire which engages with the said coil and which is provided with a laterally projecting loop having angle-shaped side portions the apices of which project downwardly below the plane of the top of the bed bottom, said loop terminating in a hook which engages with the said wire and key wire, and a space being 70 formed between the point of the said hook and the side portions of the said loop so that the hook does not require to be bent after the said parts are assembled. 75

In testimony whereof I have affixed my signature in the presence of two witnesses.

JNO. OLIVER WESNER.
